DRAPERY ROD

Hermann Dahlhaus, Ludenscheid, Westphalia, and Fritz Wust, Werdohl, Westphalia, Germany, assignors to Vossloh-Werke G.m.b.H., Werdohl, Westphalia, Germany

Filed Nov. 27, 1964, Ser. No. 83,485

Term of patent 14 years

(Cl. D21—1)

FIG. 1 is a front elevational view of a drapery rod embodying our new design;

FIG. 2 is an end view on an enlarged scale; and

FIG. 3 is an enlarged sectional view taken on the line 3—3 of FIG. 1.

The dominant features of our design reside in the portion shown in full lines with the paired transverse broken lines indicating indeterminate length.

This application is a continuation-in-part of our co-pending earlier filed application Serial Number D-76,121 filed August 6, 1963, and now abandoned.

We claim:

The ornamental design for a drapery rod, as shown and described.
